UNITED STATES PATENT OFFICE.

MAX GANTER, OF BUFFALO, NEW YORK.

DESIGN FOR AN INKSTAND.

SPECIFICATION forming part of Design No. 33,066, dated August 14, 1900.

Application filed July 19, 1900. Serial No. 24,229. Term of patent 7 years.

To all whom it may concern:

Be it known that I, MAX GANTER, a citizen of the United States, residing at Buffalo, in the county of Erie and State of New York, have invented and produced a new and original Design for Inkstands, of which the following is a specification, reference being had to the accompanying drawing, forming a part thereof.

This design relates to the configuration of an inkstand.

The accompanying drawing is a perspective view of an inkstand embodying my design.

The leading feature of my design consists of a rectangular base, a pedestal rising from the rear portion of the base, and the figure of a buffalo standing upon the pedestal.

Referring to the drawing, A is the rectangular base, having paneled walls.

B is a longitudinal groove arranged in the

top of the base near its front side, and b represents notched pen-supports arranged transversely in said groove.

C is the pedestal, which is shorter than the base and which is mounted centrally thereon in rear of the groove B. This pedestal is rectangular in form and tapers upwardly, and its sides are paneled.

D is the figure of a buffalo which surmounts the pedestal.

e represents ornaments arranged on the base on opposite sides of the pedestal.

What I claim is--

The design for an inkstand, substantially as herein shown and described.

Witness my hand this 11th day of July, 1900.

MAX GANTER.
